UNITED STATES PATENT OFFICE.

LEWIS H. LARSEN, OF RACINE, WISCONSIN, ASSIGNOR TO UNITED SHOE MACHINERY COMPANY, OF PATERSON, NEW JERSEY, A CORPORATION OF NEW JERSEY.

HOLDDOWN FOR LASTING-MACHINES.

1,218,783.

Specification of Letters Patent. Patented Mar. 13, 1917.

Application filed May 26, 1913. Serial No. 769,954.

To all whom it may concern:

Be it known that I, LEWIS H. LARSEN, a citizen of the United States, residing at Racine, in the county of Racine and State of Wisconsin, have invented certain Improvements in Holddowns for Lasting-Machines, of which the following description, in connection with the accompanying drawings, is a specification, like reference characters on the drawings indicating like parts in the several figures.

This invention relates to lasting machines and particularly to means for holding the work in bed lasting machines.

In lasting shoes upon the commercial bed lasting machines, it is necessary that the shoe be held down firmly upon the toe rest and it is important that the innersole be firmly held at and adjacent to the channel lip at and around the end of the toe because while the upper is being wiped over the edge of the last and over the feather of the innersole the innersole tends to crumple up at the channel or the rib line, or even to be displaced bodily unless it is securely held against such action. The difficulty from crumpling of the innersole has seriously increased within the past few years during which the great advance in the price of leather has obliged manufacturers, in order to keep as near as possible to the former manufacturing cost, to use a thinner innersole or one which is of less firm quality, it having been found that such an innersole will give good satisfaction provided the shoe is properly lasted and welted.

In addition to the difficulties arising from the crumpling up of the innersole at the channel and the consequent displacement of the lip which determines the stitching line by which the welt is attached around the toe, the use of these thinner and more flexible innersoles greatly increases, as would be expected, the liability that the lip or rib will be bent inwardly or overridden in lasting the toe of the shoe so that the upper materials lie upon it and render uncertain or impossible the proper stitching of the upper materials and welt to it. This difficulty is increased by the present use of bulky fabric toe stiffening material in place of the thinner but more expensive sole leather stiffeners. For these reasons it has become in-

creasingly important to provide a continuous support or abutment for the inner face of the channel lip at the tip of the toe and in order to serve its purpose adequately this support or abutment must extend backwardly a considerable distance on one or both sides of the toe but particularly on the outer side of the toe where is found the "swing" that characterizes distinctively right and left lasts. The best results in lasting toes are obtained, as I have found, by the use of a continuous or substantially uninterrupted abutment for the inner face of the channel lip around the toe, said abutment having an edge contour to fit the innersole accurately inside the lip and constituting in effect an inside former between which and the lasting plates as outside formers the upper and stiffener materials are molded and compressed into an upstanding flange against the channel lip. By so lasting the toe it is easy to sew it in the welting operation and, moreover, the inseam or line of attachment of the welt is accurately located where the designer of the shoe intended it should be and the appearance of the shoe is not adversely affected by a distorted inseam at the toe. Furthermore, since the toes of modern right and left lasts are not symmetrical with respect to the longitudinal median line, it becomes necessary in order that the lip of the innersole shall be properly supported that the shape of the means for supporting the lip of a right toe shall be the reverse of the shape of the means for supporting the lip of a left toe. Therefore for the best results a pressing member must have two pressing faces, one conforming to a right toe and one conforming to a left toe.

It is the object of the present invention to provide a hold-down device which will answer to the requirements of the trade conditions as above outlined and preferably to provide a hold-down device having two pressing faces that can be made interchangeably operative, one of which is adapted for use in lasting a right shoe and the other in lasting a left shoe.

An important feature of this invention is a hold-down device having a pressing face adapted to clamp down upon the last bottom an innersole along a line parallel to and immediately adjacent to the inner face

of the channel lip at the end of the toe and along one and preferably both sides of the toe and having a substantially continuous or uninterrupted face forming an abutment for the inner face of the lip at the tip of the toe and along one and preferably both sides of the toe as and for the purpose stated. Preferably the abutting face for the lip will extend substantially to or above the top of the lip to hold the upper portion of the lip against the pressure of the lasting plates that are located on top of the overwiped upper.

A further feature of this invention is a hold-down device comprising an arm movable over a shoe supported by a lasting machine, and a pressing member carried by said arm and having two pressing faces, one conforming to the toe portion of a right sole and the other conforming to the toe portion of a left sole, said member being adjustable relatively to the arm to make either pressing face operative or, in other words, to make the said faces interchangeably operative.

A further feature of this invention is a hold-down device comprising a pressing member and mountings therefor which member has formed on its upper and lower faces respectively two pressing faces of the character above described for use with right and left shoes, said mountings permitting detachment and inversion of the pressing member and re-attachment thereof to render operative either its pressing faces for a right shoe or its pressing faces for a left shoe. As I am advised it is new by this invention to provide a right and left hold-down device which is invertible to render a pressing face that is on one side of it operative for a right shoe and a pressing face that is on its opposite side operative for use on a left shoe.

A further feature of this invention consists in the provision for lateral angular adjustment of such a pressing member as described about an axis located near its rear end for adapting each pressing face to form the described abutment, extending along the sides and particularly the outer sides of the toe, for the channel lips of slightly different contours of right or left toes.

These and other features of the invention will appear more fully from the following detailed description when taken in connection with the accompanying drawings and will then be definitely pointed out in the claims.

Figure 1 is a perspective view of a hold-down mechanism embodying my invention and a portion of the toe head of a lasting machine;

Figs. 2 and 3 show the hold-down device detached from the transverse carrier and show the pressing member adjusted respec-

tively for a left toe and for a right toe; said member fitting in each instance against the inner face of the lip of the innersole;

Fig. 4 is a sectional view on the line 4-4 of Fig. 2;

Fig. 5 is a view of the lower face of a modified form of the hold-down foot.

At A is shown the forward portion of a toe lasting head of the commercial type of bed lasting machine, such, for example, as that shown in U. S. Letters Patent to Brock No. 1,018,477, granted Feb. 27, 1912. At B is shown a toe rest which sustains the toe portion of a shoe during the lasting operation. The operating mechanism for the hold-down is substantially similar to that disclosed and fully described in the application of Keyes, Ser. No. 580,400, to which reference may be had for details not herein given. The post 2 is mounted for vertical movement by means of a treadle not shown. The head 6 is mounted for rotation on the post 2 and supports a carrier 8 mounted to slide therein transversely of the shoe and having friction means for holding it in any position of adjustment. The inner end of the support 8 carries a headed stud upon which is detachably held a finger or arm 10 by means of a slot 12 provided for the purpose. The arm 10 extends toward the toe of a shoe supported in the lasting machine and is provided with a depending stud 14 in the rear of which is a bolt hole. A hold-down plate or pressing member 16 is provided with a hole 18 to fit the stud 14 and with a hole 20 which is located to align with the bolt hole in the arm and is countersunk on both sides. For holding the pressing member 16 securely to the arm 10 a stove bolt 22 is provided, the head of which enters the countersunk hole 20 and the body of which passes through the hole in the arm 10 and is held by a nut 24, Fig. 4. The pressing member 16 has a pressing face to engage down upon the innersole and said member is contoured to provide for so clamping the innersole at and adjacent to the base of the channel lip at the tip of the toe and along each side of the toe backwardly for a substantial distance, as shown in Figs. 2 and 3. By so clamping the innersole to the last at the base of the channel lip I successfully prevent very thin and flexible innersoles from crumpling or buckling up at the channel. The pressing member also has an edge face 26 of sufficient height to extend substantially to, and it may be above, the top of the channel lip as in Fig. 4 to present an abutment between which and the lasting plates 27 the upper and toe stiffener materials are compressed and molded into an upstanding flange in position for sewing together in the welt attaching operation.

The pressing member is contoured to present, as shown in Fig. 2, said abutment 26

in a continuous or uninterrupted line parallel to and in supporting contact with the inner face of the channel lip at the tip of the toe and along both sides of the toe back about as far as the upper materials will be fulled in wiping them over the concave edge of the toe of a left shoe.

The upper side, Fig. 2, of the member 16 is adapted to serve as a pressing face for a right shoe when said member is inverted as in Fig. 3 and from the construction described it will be evident that by removing the bolt 22 said member 16 may be slipped off of the stud 14, inverted and replaced upon the stud the other side up, in which position it may be again secured to the arm by replacing the bolt and nut, 22, 24.

By this construction is provided an invertible presser member having on its upper and lower sides respectively pressing faces shaped to fit different shoes, as for example one face conforming to the toe portion of a right shoe and the other face conforming to the toe portion of a left shoe, and means for holding said member to its carrying arm 10 with either pressing face disposed downwardly in shoe engaging position whereby said faces may be made interchangeably operative.

In Fig. 5 the pressing member 16 is formed, as for example with two holes 18, 19, to coöperate with the stud 14 in different positions of adjustment whereby said pressing member may be made to conform to slightly different widths or to somewhat varying styles of shoes, this pressing member being preferably invertible for use with both rights and lefts.

The stud 14 on the arm 10 and the hole 18 or 19 in the plate 16 constitute what are herein termed coupling members which, with the assistance of the bolt and nut 22, 24 which retain the coupling members in operative engagement, are adapted to secure the plate 16 to the arm 10 with either side facing the sole of the shoe.

Having explained the nature of this invention and described a preferred construction embodying the same I claim as new and desire to secure by Letters Patent of the United States:—

1. A lasting machine hold-down device comprising an arm movable over a shoe supported by a lasting machine and a pressing member connected with said arm and provided with two pressing faces, one conforming to the toe portion of a right sole and the other to the toe portion of a left sole, said faces being interchangeably operative.

2. A lasting machine hold-down device comprising an arm movable over a shoe supported by a lasting machine, a pressing member having two pressing faces, one conforming to the toe portion of a right sole and the other to the toe portion of a left

sole, and connections between said arm and pressing member whereby said faces may be made interchangeably operative.

3. A lasting machine hold-down device comprising an arm movable over a shoe supported by a lasting machine, an invertible presser member having on its upper and lower sides, respectively, pressing faces shaped to fit different shoes, and means for holding said member to the arm with either pressing face of the member disposed downwardly in shoe engaging position.

4. A lasting machine hold-down device comprising an arm movable over a shoe supported by a lasting machine and a pressing member connected with said arm and provided with two pressing faces, one conforming to the toe portion of a right sole and the other to the toe portion of a left sole, said arm having a stud 14, a pressing member having a hole 18 to coöperate with the stud and a second hole 20, and means engaging the hole 20 for detachably securing the member to the arm to permit said pressing faces to be made interchangeably operative.

5. A lasting machine hold-down device comprising an arm movable over a shoe supported by a lasting machine and a pressing member connected with said arm and provided with a pressing face conforming to the toe portion of a shoe, said arm having a stud 14 and the pressing member being formed to coöperate with the stud for holding the member in different positions of adjustment, and means 22 for securing the member to the arm in its different positions of adjustment.

6. A lasting machine hold-down device comprising an arm movable over a shoe supported by a lasting machine and a pressing member connected with said arm and provided with a pressing face adapted to clamp down upon the last bottom an innersole along a line parallel to and immediately adjacent to the inner face of the channel lip at the end of the toe and along a side of the toe and having a substantially continuous edge face extending from the plane of the sole substantially to the top of the lip and forming an abutment for substantially the full height of the inner face of the lip at the tip of the toe and along the side of the toe, as and for the purpose described.

7. A lasting machine hold-down device comprising an arm movable over a shoe supported by a lasting machine, and having a coupling member, and a hold-down plate having a complementary coupling member detachably engageable with the arm coupling member, said coupling members being adapted to secure the plate to the arm with either side facing the sole.

8. A lasting machine hold-down device comprising an arm movable over a shoe sup-

ported by a lasting machine, and having a coupling member, a hold-down plate having a complementary coupling member detachably engageable with the arm coupling member, said coupling members being adapted to secure the plate to the arm with either side facing the sole, and means for retaining the coupling members in operative engagement.

10 9. A lasting machine hold-down device comprising supporting means and a pressing member operatively connected with the supporting means and having an edge face contoured to abut against and lie in substantially continuous contact with the inner face of an innersole rib, said member being reversible relatively to its supporting means to cause said edge face substantially to fit pronounced reverse curvatures in rib contour of right and left toes whereby the same member may be used with equal effect in lasting both right and left shoes.

10 10. A lasting machine hold-down device comprising supporting means and a pressing member operatively connected with the supporting means and having an edge contour adapted to fit against the inner face of the innersole rib around the toe of an innersole of a given size having pronounced 30 right and left curvatures and reversible relatively to its supporting means to adapt it to fit substantially reverse curvatures in rib contour of right and left toes whereby the same edge of the pressing member may 35 be used with equal effect in lasting both right and left shoes of the same size.

11 11. A lasting machine hold-down device comprising supporting means, a pressure member operatively connected with the supporting means and having an edge face contoured to adapt it to fit against the inner face of an innersole rib of a shoe of a given style, said member being constructed and arranged for adjustment upon its supporting means into two predetermined positions reversely inclined to the longitudinal median line of the forepart of the innersole, and means for positively holding the member from movement relatively to the supporting means in either of said predetermined positions.

12 12. A lasting machine hold-down device comprising supporting means and a pressing member operatively connected with the supporting means and having an edge face of a permanent shape and contoured to abut against the inner face of an innersole

rib, said member being arranged for reversal relatively to its support to adapt the said edge face to fit substantially reverse shapes in rib contour of right and left toes whereby the same member may be used with equal effect in lasting both right and left shoes.

13. A lasting machine hold-down device comprising an arm movable over a shoe supported by a lasting machine, and a plate provided with a pressing face conforming substantially to the contour of the toe portion of a shoe sole, said arm having a stud and the plate having holes to fit the stud for supporting the plate in different positions of adjustment, and means for securing the plate in such positions.

14. A lasting machine hold-down device comprising an arm movable over a shoe supported by a lasting machine, and a plate provided with a pressing face conforming to the toe portion of a shoe sole, said arm and member being provided with coupling connections permitting adjustment of the plate about a vertical axis while the plate remains attached to the arm and arranged to hold the plate positively in either of a plurality of positions of adjustment about said axis.

15. A lasting machine hold-down device comprising an arm movable over a shoe supported by a lasting machine, and a plate provided with a pressing face conforming substantially to the contour of the toe portion of a shoe sole, said arm and plate being connected together for relative adjustment about a vertical axis, and interengaging formations upon the arm and member for maintaining the member and the arm positively in different positions of adjustment about said axis.

16. A lasting machine hold-down device comprising an arm movable over a shoe supported by a lasting machine, a presser member on said arm constructed and arranged for angular adjustment about a vertical axis, and positively acting means for holding the member in a plurality of predetermined positions of adjustment.

In testimony whereof I have signed my name to this specification in the presence of two subscribing witnesses.

LEWIS H. LARSEN.
